(57) **CLAIM**

The ornamental design for a clutch bag, as shown and described.

DESCRIPTION

1. Clutch bag

1.1 : Perspective

1.2 : Front

1.3 : Back

1.4 : Right

1.5 : Left

1.6 : Top

1.7 : Bottom

1.8 : Perspective view in a state of use

The clutch bag has a flattened body, with a zipper on the front side; in its upper portion the body has two circular through-holes which are horizontally aligned and connected by a horizontal slot; the figures show, in sequence, the clutch bag in perspective view, front view, rear view, right-hand view, left-hand view, top view and bottom view, and in perspective view in a state of use; in all the attached photographs the dotted lines represent seams which are not claimed; in fig. 1.8 the dotted graphic part represents an example of a bag with which the clutch bag can be used; said bag is not part of the design and is not claimed.
